UNITED STATES PATENT OFFICE.

FRANK TAYLOR EVANS, OF THE UNITED STATES NAVY, ASSIGNEE TO GEORGE HILLARD BENJAMIN, OF NEW YORK, N. Y.

METHOD FOR OBTAINING PURE WATER FROM SALT WATER.

1,225,118.

Specification of Letters Patent.

Patented May 8, 1917.

Application filed July 1, 1913. Serial No. 776,755.

To all whom it may concern:

Be it known that I, FRANK TAYLOR EVANS, a citizen of the United States and an officer in the United States Navy, (whose post-office address is Navy Department, Washington, District of Columbia,) have invented a new and useful Improvement in Methods for Obtaining Pure Water from Salt Water, of which the following is a specification.

10 My invention depends upon the following observed facts:

(1) That the vapor derived from salt water, when such salt water is in a state of agitation, (as for instance is the case with 15 salt water contained within a condenser located on a torpedo boat and in a sea-way) when subjected to heat, always contains more or less salt.

(2) That if the vapor derived from the evaporation of salt water is superheated, the resultant vapor will be free from salt and may be condensed in the usual manner to obtain pure water.

To carry my invention into effect, I proceed in the manner and may make use of the apparatus which I will now describe.

Figure 1 is a diagrammatic view, partially in section and partially in elevation, showing an evaporator, a superheater and a condenser, with the tubes through which the salt water circulates in the condenser, shown in dotted lines. Fig. 2 is a plan view of the apparatus shown in Fig. 1, and illustrates that two superheaters may be used, either 25 singly or as a pair. The method may be carried into effect in the following manner:

Salt water is introduced through a pipe A, into the shell of an evaporator B, provided with a heating coil C, on the end of which 30 is a water trap D. The water, as it is evaporated, forms a vapor, which passes from the top of the evaporator, through pipe E, into the bottom of the shell of an evaporator F, provided with a superheating coil G. The vapor leaves the top of the shell of evaporator F and passes by pipe H into the upper 35 part of the condenser I, provided with cooling coils J. The cold, pure water leaves the condenser I at the bottom through the pipes K. I do not in any wise limit myself to the type of the evaporator, the superheater or the condenser which may be used.

In practice I prefer to pass the steam through the heating coil G of the superheater F, at a pressure of approximately

250 lbs. to the square inch, and successively through the heating coil C of the evaporator B, at approximately 75 lbs. to the square inch. To regulate the pressure in the heating coil C, I may make use of the valve L. 40 A and M represent pipes through which fresh water may be introduced and discharged to wash out the accumulated salt, and N and O, similar pipes in the superheater F, such pipes provided with suitable 45 valves.

In Fig. 2, two superheaters are shown, F and F¹, in which case the pipe B is connected to a pipe P communicating with the superheater F and the superheater F¹, and provided with valves Q and Q¹, which may be opened or closed to throw the vapor circuit through one or both of the superheaters. The terminals of the heating coils G of each of the superheaters is connected with the 50 heating coil C of the evaporator, and valves R and R¹ are provided to control the passage of steam. It will be observed from the drawings that the heating coils G of the superheater F or F¹ are in tandem with the coil 55 C of the evaporator B. This arrangement is of advantage as it permits the utilization of all the units of the heat of the steam originally introduced into the superheater.

One of the advantages of my improved 60 method and apparatus is that a very much higher rate of evaporation can be accomplished than in evaporators as now used, where baffle-plates or baking the vapor is employed to decrease the percentage of salt 65 carried over with the vapor from the evaporator.

Having thus described my invention, I claim:

1. The method described for obtaining 70 pure water from salt water in a state of agitation, which consists in first subjecting such salt water to heat to set free a vapor containing water and a small percentage of salt, then superheating the vapor so derived to 75 obtain a second vapor containing water but no salt, and finally condensing the last named vapor.

2. The method described for obtaining 80 pure water from salt water in a state of agitation, which consists in first subjecting such salt water to sufficient heat to set free a vapor containing water and a small percentage of salt, then subjecting the vapor so derived to 85 a very much higher degree of temperature 90

- to set free a second vapor containing water but no salt, and finally condensing the last named vapor.
3. The method described for obtaining 5 pure water from salt water in a state of agitation, which consists in first subjecting such salt water in a closed vessel to the action of sufficient heat to set free a vapor containing water and a small percentage of salt, then 10 subjecting said vapor so derived in a closed vessel to a very much higher temperature to set free a second vapor containing water but no salt, and finally condensing the last named watery vapor.
- 15 4. The method described for obtaining pure water from salt water in a state of agitation, which consists in evaporating salt water by heat to obtain a watery vapor containing a small percentage of salt, then super- 20 heating the vapor so derived under conditions where no water is present as a body, and finally condensing the superheated vapor to obtain pure water.

5. The method described for obtaining 25 pure water from salt water in a state of agitation, which consists in introducing a body of salt water into a vessel and therein subjecting such salt water to the action of heat transmitted through the water from a coil through which steam is passed, conveying the 30 vapor thus derived from such vessel to a second vessel, and therein subjecting such vapor to the action of heat transmitted through the vapor from a coil through which steam of higher temperature is passed, whereby such 35 vapor is expanded to form a second vapor and the salt separated therefrom, condensing the last named vapor to form fresh water, and removing the deposited salt from time to time.

In testimony whereof, I affix my signature, in the presence of two witnesses.

FRANK TAYLOR EVANS.
